UNITED STATES PATENT OFFICE.

JAMES WILLIAM FRASER, OF CHARLOTTE, NORTH CAROLINA.

POLE-TOP CAP.

No. 872,822.

Specification of Letters Patent.

Patented July 7, 1908.

Application filed November 11, 1907. Serial No. 401,581.

To all whom it may concern:

Be it known that I, JAMES WILLIAM FRASER, a subject of the King of England, residing at Charlotte, in the county of Mecklenburg and State of North Carolina, have invented a new and useful Improvement in Pole-Top Caps, of which the following is a specification.

My invention is an improvement in pole-top caps, and consists in certain novel constructions and combinations of parts hereinafter described and claimed.

Referring to the drawings forming a part hereof, Figure 1 is a side view of a pole provided with the improved cap and Fig. 2 is a plan view of the cap partly in section.

In the present embodiment of the invention, the pole A has its top squared, and the cap B rests thereon, the pole being extended a short distance above the highest cross arm *a* in the usual manner.

The cap comprises a flat plate *b* of the shape shown in Fig. 2 and of suitable material, and is provided on its lower face at its large end *b*¹ with a socket *b*², in which is received the top of the pole. The sides of the socket are extended as at *b*³ *b*⁴ to engage the sides of the pole, and the said extended sides are provided with openings for receiving lag screws *b*⁵, for securing the cap to the pole.

The upper face of the plate at the large end, is provided with an opening *b*⁶, into which is threaded the insulator pin *b*⁷, bearing on its end the usual insulator *b*⁸, which is provided on its top with the groove *b*⁹, for receiving the wire *c*.

The small end of the plate is provided with a head *b*¹⁰, having a vertical depression or groove *b*¹¹ on its outer face in which is received an arm, in the present instance a pipe D, the pipe being secured to the head by a U-bolt *b*¹², whose threaded arms traverse openings in the head, and are secured in place by nuts *b*¹³.

The pipe D extends vertically upward from the head, as at *d*, and the upper end is flattened as at *d*¹. A wire E for lightning protection is supported at the junction of the flattened portion with the main portion of the pipe. This wire is retained in position by a U-bolt *d*², the threaded arms of which traverse openings in the flattened portion and are retained in place by nuts *d*³.

It will be noticed that the flattened portion of the pipe extends above the wire E as at *d*⁴, and that the portion *d*⁵ of the pipe below

the head, is bent at an angle to the portion above the head, and engages the pole as at *d*⁶, the engaging portion being also flattened and provided with an opening, through which passes a bolt *d*⁷, the bolt also passing through the pole, and being secured by a nut *d*⁸.

A ground wire G is arranged longitudinally of the pole in the usual manner, the lower end being grounded, and the upper end is formed into a loop and inserted between the head of the bolt and the flattened portion of the pipe, before the nut is tightened. After the bolt is tightened the ground wire is pressed into firm contact with the pipe.

A horn arrester F, as shown in Fig. 1, is connected with the top of the insulator as at *f*. The distance from the horn arrester to the pipe is somewhat less than the sparking distance from the line wire to the insulator pin, and is designed to carry abnormal charges of electricity from the line wire to the pipe. The extended part of the flattened portion of the pipe above the lightning protector wire is for the purpose of preventing injury to said wire by the discharge from the horn arrester. A resistance may be inserted in series in the ground wire if desired.

It will be understood that the part D is of conducting material, and while I have described it as a pipe it is obvious that it might be of any other suitable form or shape. The cap provides a secure fastening for the insulator pin, and also protects the pole from the weather. The cap may also be used without the horn arrester.

It will be evident that the cap comprises a socket for receiving the end of the pole and provided with an opening for engagement by an insulator pin, and a lateral extension from the socket for supporting an arm having at one end, means for supporting a protector wire, and at the other a means for attachment to a ground wire. The lateral extension spaces the protector wire and the arm away from the line wire.

I claim

1. The combination with the pole provided with a ground wire of a pole top cap, comprising a plate having one of its ends widened, and provided on its lower face with a socket for receiving the end of the pole, said end having on its upper face an opening, an insulator pin mounted therein, an insulator for supporting a line wire on the pin, a horn arrester in connection with the wire at the pin, an arm of conducting material con-

nected with the opposite end of the plate, said plate being provided with a groove for receiving the arm, a U-bolt engaging the arm and having threaded arms traversing in the head, nuts engaging the threaded ends, the arm extending above and below the head, the upper end being provided with means for supporting a wire, and the lower end being bent at an angle to the upper end and engaging the pole, and a bolt traversing the arm and pole, the end of the ground wire being received between the head of the bolt and the arm.

2. The combination with the pole provided with a ground wire, of a plate having at one end a socket on its lower face for receiving the end of the pole, and an opening on its upper face, an insulator pin supported in the opening, an arm connected with the other end of the plate, said arm extending above and below the socket, the upper end being provided with means for supporting a protector wire, and the lower end being bent at an angle to the arm, and engaging the pole, and a bolt traversing the arm and pole, the end of the ground wire being received between the head of the bolt and the arm.

3. The combination with the pole, provided with a ground wire, of a plate having at one end a socket for receiving the top of the pole, and an opening for receiving the insulator pin, an arm connected with the other end of the plate, said arm extending above and below the plate, the upper end being provided with means for supporting a protector wire, and the lower end engaging the pole and having a connection with the ground wire.

4. The combination with the pole pro-

vided with a ground wire, of a plate having at one end a socket for receiving the top of the pole, and an opening for receiving an insulator pin, an arm connected with the other end of the plate, said arm extending above and below the plate, the upper end being provided with means for supporting a protector wire, and the lower end being connected with the ground wire.

5. A pole top cap comprising a plate having a socket for receiving the end of the pole, and an opening for receiving an insulator pin, a vertical arm connected with the other end of the plate, the upper end of the arm being provided with means for supporting a protector wire, and the lower end being adapted for connection with a ground wire.

6. A pole top cap, comprising a socket for receiving the end of the pole, said socket having an opening for engagement by an insulator pin, and a lateral extension, a vertical arm supported by the extension, the upper end of said arm being provided with means for supporting a protector wire, and the lower end being adapted for connection with a ground wire.

7. A pole top cap, comprising a socket for receiving the end of the pole, said socket having a means for engagement by an insulator pin, a lateral extension and means supported by the extension for supporting a protector wire, said means being adapted for connection with a ground wire.

JAMES WILLIAM FRASER.
